[57] CLAIM

The ornamental design for a turkey decoration, as shown and described.

DESCRIPTION

FIG. 1 is a perspective view of a turkey decoration showing my new design in use;
FIG. 2 is a front elevational view of tail feathers of the turkey, shown separately for clarity of illustration;
FIG. 3 is a rear elevational view of FIG. 2;
FIG. 4 is a left side elevational view of FIG. 2, the right side being a mirror image thereof;
FIG. 5 is a top plan view of FIG. 2;
FIG. 6 is a bottom plan view of FIG. 2;
FIG. 7 is a top plan view of a left wing of the turkey, shown separately for clarity of illustration;
FIG. 8 is a bottom plan view of FIG. 7;
FIG. 9 is a right side elevational view of FIG. 7;
FIG. 10 is a left side elevational view of FIG. 7;
FIG. 11 is a rear elevational view of FIG. 7;

FIG. 12 is a front elevational view of FIG. 7;
FIG. 13 is a top plan view of a right wing of the turkey, shown separately for clarity of illustration;
FIG. 14 is a bottom plan view of FIG. 13;
FIG. 15 is a right side elevational view of FIG. 13;
FIG. 16 is a left side elevational view of FIG. 13;
FIG. 17 is a rear elevational view of FIG. 13;
FIG. 18 is a front elevational view of FIG. 13;
FIG. 19 is a front elevational view of a head of the turkey, shown separately for clarity of illustration;
FIG. 20 is a rear elevational view of FIG. 19;
FIG. 21 is a left side elevational view of FIG. 19, the right side being a mirror image thereof;
FIG. 22 is a top plan view of FIG. 19;
FIG. 23 is a bottom plan view of FIG. 19;
FIG. 24 is a perspective view of an alternate embodiment of my new design;
FIG. 25 is a front elevational view of tail feathers of the turkey of FIG. 24, shown separately for clarity of illustration;
FIG. 26 is a rear elevational view of FIG. 25;
FIG. 27 is a left side elevational view of FIG. 25, the right side being a mirror image thereof;
FIG. 28 is a top plan view of FIG. 25;
FIG. 29 is a bottom plan view of FIG. 25;
FIG. 30 is a top plan view of a left wing of the turkey of FIG. 24, shown separately for clarity of illustration;
FIG. 31 is a bottom plan view of FIG. 30;
FIG. 32 is a right side elevational view of FIG. 30;
FIG. 33 is a left side elevational view of FIG. 30;
FIG. 34 is a rear elevational view of FIG. 30;
FIG. 35 is a front elevational view of FIG. 30;
FIG. 36 is a top plan view of a right wing of the turkey of FIG. 24, shown separately for clarity of illustration;
FIG. 37 is a bottom plan view of FIG. 36;
FIG. 38 is a right side elevational view of FIG. 36;
FIG. 39 is a left side elevational view of FIG. 36;
FIG. 40 is a rear elevational view of FIG. 36;
FIG. 41 is a front elevational view of FIG. 36;
FIG. 42 is a front elevational view of a head of the turkey of FIG. 24, shown separately for clarity of illustration;
FIG. 43 is a rear elevational view of FIG. 42;

FIG. 44 is a left side elevational view of FIG. 42, the right side being a mirror image thereof;

FIG. 45 is a top plan view of FIG. 42; and,

FIG. 46 is a bottom plan view of FIG. 42.

The broken line showing of a pumpkin in FIGS. 1 and 24 is for illustrative purposes only, and forms no part of the claimed design.
